UNITED STATES PATENT OFFICE.

WILKENS A. SCHENCK, OF PHILADELPHIA, PENNSYLVANIA.

DRAWING-PEN.

1,304,709.

Specification of Letters Patent. Patented May 27, 1919.

Application filed May 20, 1918. Serial No. 235,521.

To all whom it may concern:

Be it known that I, WILKENS A. SCHENCK, a citizen of the United States, residing at 44 N. 4th street, Philadelphia, in the county 5 of Philadelphia and State of Pennsylvania, have invented new and useful Improvements in Drawing-Pens, of which the following is a specification.

The invention relates to pens and more 10 particularly to drafting pens for use by draftsmen and the like, and has for an object to provide a ruling pen of the class mentioned which can be cheaply and easily manufactured; in which the nibs can be 15 moved apart for cleaning purposes without disturbing the manner in which they are relatively set when they are closed; in which one of the legs has a greater resiliency and spring-like action than the other, and in 20 which the point of spring action is removed from the point of connection of the pen proper with the handle, to prevent wear at that point.

Among other features, the invention 25 comprehends a ruling pen in which the body of the pen can be formed of a single piece of material, namely, a blank, the latter when formed into the finished product providing a shank and relatively arranged legs terminating in nibs, which are connected by a 30 screw, and therefore relatively adjusted at the nib ends, and a handle having connection with the pen proper at the shank, the shank being so formed and designed that the 35 spring action that is necessary will be entirely on the part of one of the legs, and said spring action will be removed from the point of connection of the handle with the pen body, so as to prevent any wearing out 40 of the usual thread employed in connecting the handle to the pen proper.

In the further disclosure of the invention, reference is to be had to the accompanying drawing, constituting a part of this specification, in which similar characters of reference denote corresponding parts in all the views, and in which—

Figure 1 is a side elevation of the pen.

Fig. 2 is a similar view showing the spring 45 leg in open or normal position.

Fig. 3 is a front elevation.

Fig. 4 is a sectional enlarged view taken on the line 4—4 of Fig. 1.

Fig. 5 is a fragmentary side elevation of a modified form, and

Fig. 6 is a plan view of the blank from which the pen is formed.

Referring more particularly to the views the blank, indicated by the numeral 10, consists of any good form of steel and, as shown, 60 provides a shank 11 at the medial portion, said shank being enlarged relative to the rest of the blank, with legs formed by the parts of the blank extending from the shank, said legs being indicated by numerals 12 65 and 13. The blank is of course bent upon itself at the shank 11, and thus the legs 12 and 13 will be arranged, as shown in Figs. 1 to 4 inclusive. The shank 11 is provided with an aperture 14 through which extends 70 a threaded stud 15 of a handle 16, thus holding the pen body and handle together. A suitable adjusting screw 17 passes loosely through an opening 18 in the leg 13, and is threaded through an opening 19 in the leg 75 12, thus permitting of the relative adjustment of the nibs of the legs, indicated by numerals 20, 21, whereby the nibs can be spaced apart a sufficient distance for cleaning, and when drawn together again, by 80 tightening up the screw 17, the set of the pen will not have been disturbed.

Particular attention is called to the construction of the shank 11, and which it will be noted is so formed that one side of the 85 shank, namely, the side from which the leg 13 extends, is reduced in thickness at a point 22 relative to the other shank from which the leg 12 extends, and which it will be seen is substantially thicker than the part of the 90 shank at 22. By having this form of construction, the spring-like action or resiliency that is necessary in a ruling pen, is all in the leg 13 and that part of the shank from which the leg 13 extends, so that the spring 95 action will be centered substantially at the point 22 and, as shown in Fig. 2, when the screw 17 is removed or loosened, the leg 13 will move away from the leg 12, the latter remaining substantially stationary relative 100 to the handle 16. With this arrangement a greater spring-like action and resiliency is obtained, and one that is absolutely positive in preventing any disturbance of the setting of the pen, for the reason that the 105 movable leg will naturally move toward the

stationary leg when the screw is tightened to bring the nibs 20, 21 into their proper relation. Further, by having the point of spring action at 22, rather than at the point 5 of connection of the handle with the pen body, the wearing out of the stud 15 will be prevented, and the removal of the strain from this point results in a more durable 10 ruling pen, having greater strength and more lasting qualities. It will be noted that the side of the shank from which the leg 12 extends has a substantially curved face 23; whereas, the side of the shank from which the leg 13 extends, has its face 24 flat 15 but inclined relative to the handle 16 or to the vertical axis of the pen, and it is by the reduction in thickness of this side of the shank that I accomplish my result, namely, 20 the provision of a pen in which the upper leg will be the moving element and have the spring-like action that is necessary to a ruling pen.

In Fig. 5 I show a slightly modified form 25 of my invention and in which both sides or faces 23, 24 of the shank 11 are reduced in thickness at the points 22^a, 22^b, and thus each leg will have the same resiliency without having the strain of the spring-like action centered at the point of connection of

the handle 16 with the pen body, but of course 30 it will be understood that I prefer the construction shown in Figs. 1 to 4 inclusive.

Aside from the spring-like quality secured by a pen of this character, I will be enabled, 35 by having the pen body made from a blank, to manufacture the pen at a far lower cost than ruling pens are now manufactured, and which are made in two pieces brazed together, or in some other such form. 40

By reference to Fig. 4 it will be seen that the reduction in thickness of the shank at the point 22 is considerable when compared with the thickness of the shank on the opposite side thereof. 45

I claim:

As a new article of manufacture, a ruling pen comprising a handle and a single piece of elongated metal bent at its medial portion to form blades terminating in nibs, the 50 medial bent portion being perforated to receive a stud whereby the pen is secured to the handle, and said piece of elongated metal being reduced in thickness adjacent the medial bent portion to give the requisite spring 55 to one of the blades or a plurality thereof.

In testimony whereof I affix my signature.
WILKENS A. SCHENCK.
